DESIGN.

—o—
O. T. JENNINGS.

GLOVE OR MITT.

No. 16,944.

Patented Oct. 19, 1886.

UNITED STATES PATENT OFFICE.

OLIVER T. JENNINGS, OF BROOKLYN, NEW YORK, ASSIGNOR TO A. G. JENNINGS & SONS, OF SAME PLACE.

DESIGN FOR A GLOVE OR MITT.

SPECIFICATION forming part of Design No. 16,944, dated October 19, 1886.

Application filed September 9, 1886. Serial No. 213,171. Term of patent 7 years.

To all whom it may concern:

Be it known that I, OLIVER T. JENNINGS, a resident of Brooklyn, in the county of Kings and State of New York, have invented and 5 produced a new and original Design for Gloves and Mitts, of which the following is a full, clear, and exact description, reference being made to the accompanying photograph, which represents a side view of a mitt having my invention.

This invention relates to a new ornamentation and configuration of the arm portion of a glove or mitt; and it consists in the design for said arm portion having outwardly-projecting 15 irregular loops which are ranged in longitudinal straight stripes that surround the arm portion of the glove or mitt, thereby producing a peculiar effect.

In the accompanying photograph, the letter A represents the hand portion of a glove or mitt. B is the arm portion of the same. This arm portion has series of longitudinal straight stripes *b* surrounding it, each stripe being composed of series of irregular outwardly-projecting loops *a*. These fur-like stripes *b* are separated by plain stripes *d*, as shown.

I claim—

The design for the arm portion B of a glove or mitt, the same consisting of the longitudinal straight stripes *b*, composed of loops *a*, which surround said arm portion, alternating with the plain stripes *d*, substantially as shown.

OLIVER T. JENNINGS.
